(74) Attorney, Agent, or Firm — Olson & Cepuritis, Ltd.;
Shawn E. Duckworth, Esq.

(57) **CLAIM**

The ornamental design for a pair of exhaust pipes, as shown and described.

DESCRIPTION

1. Pair of exhaust pipes

1.1 is a top, rear, and right side perspective view of a pair of exhaust pipes embodying our new design;

1.2 is a right side elevation view thereof;

1.3 is a left side elevation view thereof;

1.4 is a top plan view thereof;

1.5 is a rear elevation view thereof;

1.6 is a front elevation view thereof;

1.7 is a front and left side perspective view thereof;

1.8 is a top and left side perspective view thereof; and

1.9 is a bottom plan view thereof.

1 Claim, 9 Drawing Sheets
